UNITED STATES PATENT OFFICE.

EUGENE H. TAYLOR, OF HYDE PARK, MASSACHUSETTS.

INSOLE-FORMING MACHINE.

1,152,131.

Specification of Letters Patent. Patented Aug. 31, 1915.

Application filed April 1, 1914. Serial No. 828,736.

To all whom it may concern:

Be it known that I, EUGENE H. TAYLOR, a citizen of the United States, residing at Hyde Park, county of Norfolk, State of Massachusetts, have invented a certain new and useful Improvement in Insole-Forming Machines, of which the following is a specification, reference being had therein to the accompanying drawings.

10 My invention relates to a novel machine for forming an insole of the general type shown in U. S. Letters Patent No. 1,062,536 dated May 20, 1913 although it is not of the type claimed therein, said insole to be used

15 in the manufacture of welt boots and shoes. Heretofore in the manufacture of welt boots and shoes it has been common to prepare the insole for attaching the upper and welt by making an incision about a portion of the

20 edge of the insole and thereby forming a channel flap which is turned up and secured to the upper and welt by stitching. The channel flap thus formed, however, is necessarily thinner than the insole and therefore, in order that the channel flap shall have sufficient strength it is essential that a relatively thick and expensive piece of leather be employed for the insole. The insole shown in the said Letters Patent has

25 the advantage of having an integral channel flap or lip of as thick material as that of which the rest of the insole consists, but, so far as known to me, there has been no machine produced which will practically 30 and commercially produce insoles in general like those shown and described therein.

My invention has, therefore, for its object to produce a machine which will make the said insoles rapidly and well.

35 My invention will be fully understood from the following description taken in connection with the accompanying drawings and the novel features will be pointed out and clearly defined in the claims at the close of the specification.

Figure 1 is a plan view partly broken away of a machine embodying my invention showing the forming dies opened up and the machine ready for the reception of 50 a blank. Fig. 2 is a front elevation partly broken away of a machine embodying my invention. Fig. 3 is a plan view similar to Fig. 1 but showing the position occupied by the parts when there is a blank on the shaping-die under compression. Fig. 4 is a section on line 4-4 of Fig. 3. Fig. 5 is a view

of the blank. Fig. 6 is a view in perspective of the blank in the form of an insole after having been shaped in the machine. Fig. 7 is a sectional view of a machine embodying 60 my invention equipped with a shaping-die adapted to form the inner insole member. Fig. 8 is a view in perspective of the inner blank after having been shaped in the machine shown in Fig. 7. Figs. 9 and 10 are 65 sections showing successive positions of the operating members during the shaping of the outer insole member. Fig. 11 illustrates the use of the machine for the purpose of assembling the insole members. 70

Having reference to the drawings and particularly to Figs. 1, 2, and 3, there is shown at A a flat table or bed plate provided with legs or supporting members B and carrying a suitable die-supporting 75 frame or yoke C. The table A is provided, substantially centrally thereof, with a longitudinal opening 11 having at the sides oppositely disposed guideways 12 and 13, and at one end a guideway 14. The frame C is 80 rigidly secured to the table and supports a forming die 15 carried on the lower end of a slide rod 16 slidably mounted in the guides 17 which are preferably integral with the frame C. 85

The shaping-die consists of a flat plate 19 which is of the proper size and shape for the particular insole to be formed and has about its lower edge a horizontal lip or flange 20 as is shown in Figs. 1 and 3. The 90 flange or lip 20 may be made integral with the plate 19 or it may be formed by a thin plate secured to the bottom of plate 19. The plate 19, which is preferably relatively thick, is supported by a suitable head 21 to which 95 it is detachably secured by bolts 22. Integral with the head 21, is a collar 10 adapted to receive the end of the slide rod 16, being secured to it by a set screw 18, so that the shaping-die may be quickly changed from 100 time to time as required for different sizes and styles of shoes.

The shaping-die is so located that it is directly above the opening 11. The slide rod 16, which supports it is given a reciprocating movement by means of a toggle joint consisting of an elbow lever pivoted at 24 to the frame C, one arm 23 of the elbow lever forming the handle and the other arm 25 being connected to the link 26 105 at 27. The other end of the link 26 is pivotally secured to the collar 10 fast on the 110

slide rod 16 as shown in Fig. 4. The downward movement of the rod 16 is limited by a suitable collar 30 which strikes against the lower guide member 17 adjustably secured to the slide rod by a screw 31. By this arrangement the length of the downward stroke may be adjusted as desired for reasons hereinafter to be set forth.

In conjunction with the shaping-die 15, I employ a yieldingly mounted work-support 32 which is carried by a slide rod 33 mounted in the guides 34 integral with the supporting member D, and secured to the bottom of the table A as shown in Fig. 2. The work-support 32 comprises a horizontal member or plate having a flat upper surface, parallel with the lower surface of the shaping-die, and a collar 35 to receive the upper end of the slide rod 33. The work-support is secured to the slide rod 33 by a set screw 36 and may be removed from the machine when required. A helical spring 37 surrounds the slide rod 33, and is interposed between the lower guide 34 and a collar 38 fast on the shaft. The spring tends to move the shaft upwardly, its upward movement being limited, however, by the upper guide 34 against which the collar 38 strikes. The work-support is located directly below the shaping-die 15 and is approximately of the same size and shape as its lower surface. When the work-support is in the position normally given it by the spring 37, it is slightly above the table as shown in Fig. 2.

The shaping-die and work-support act in conjunction with what may be termed external forms which are slidably mounted on the upper surface of the table A in a manner clearly shown in Figs. 1 and 3. The external forms comprise side forms or presser members 39 and 40 and an end form 48. The side forms are supported on plates 41 to which they are secured by set screws 42. The plates 41 are each in turn secured to T-members 43 located in the slots or guideways 12 and 13, the T-extension 45 of which extends through and snugly fits within the slots. In order that the plates may be adjusted relatively to the shaping-die I provide slot and pin connections 46 with the T-members 43 all as clearly appears in Figs. 1 and 3. The T-extensions 45 of the T-members 43 extend downwardly to the lower surface of the table A and in order to prevent the T-members from having a tendency to move upwardly I provide each with a flat plate 47 which extends outwardly at each side beyond the T-extensions and lies contiguous with the lower lower surface of the table. The side form 39 consists preferably of a relatively thick flat plate, the compressing or operating surface of which lies adjacent the edge of the bottom plate 19 of the shaping-die and has a contour or outline

which exactly corresponds with that of the shaping-die plate. In the same manner, the side form 40 has an operating surface which corresponds with the opposite side of the plate 19 so that when the forms are placed along the sides of said shaping-die plate they make a substantial fit therewith.

The toe form 48 referred to above is secured to a plate 49 which is in turn adjustably secured to a T-member 501 supported on the table A in the same manner as the other T-members described above. The toe form 48 also consists of a relatively thick flat plate having an operating surface adapted to co-operate with that of the extreme toe portion of the plate 19. As is shown in Figs. 1 and 3, the operating surface of the toe form comprises two substantially straight surfaces 50 and 51 connected by a curved surface 52. The side forms 39 and 40 have extensions 53 and 54 respectively which extend almost to the toe of the shaping-die, and the forms are so arranged that when they are pressed together, in a manner hereinafter to be described, the toe form co-operates with the side forms and the entire toe portion of the shaping-die plate 19 is contiguous with the operating surface of the forms with the exception of the surface 52 which is preferably spaced slightly from the toe of the shaping-die plate 19 as shown in Fig. 3 for reasons hereinafter to be set forth.

The arrangement for mounting the forms hereinabove described is important for the forms are thereby rendered interchangeable and the operator may make both rights and lefts on the same machine and with the same forms by interchanging the forms. This may be done by securing the side forms 39 and 40 to the other side of the plates 41 and securing each of the plates 41 to the opposite side from that on which it was before. The toe form 48 is then turned over. It will thus be seen that the machine is adapted to shape and form insoles for both left and right shoes by the same forms.

The external forms are movable toward and away from the shaping-die 15 in the slots 12, 13 and 14 in which the T-members are mounted, and uniform and simultaneous movement is imparted to them by a toggle joint construction which may be operated by hand lever 55 or by other suitable mechanism. The hand lever 55 is pivoted at 56 to the lower side of the table A as shown in Figs. 1, 2, and 3 and is provided with a short elbow extension 57. A link 58 is pivoted as shown at 59 so that movement is imparted to it by the lever 55. The free end of the link 58 is pivotally secured to a member 60 having a fulcrum at 61 and connected in turn with the plate 47 by means of a link 62 pivoted at 63 and 64. The hand lever 55 is also connected with the form 39 by means

of a link 65 pivoted at 66 to the lever and at 67 to a member 68 having a fulcrum at 69 secured to the table and connected with the form 39 through a link 70 and suitable 5 pivots 71 and 72. It will be readily seen from the above that the movement of the lever 55 from the position shown in Fig. 1 to that shown in Fig. 3 will cause the forms 39 and 40 to be moved inwardly with a unit 10 form movement and be brought forcibly to bear against the sides of the shaping-die plate 19. The toe form 48 is also moved inwardly by the movement of the said lever by the short link 73 pivoted at one end to 15 the lever 55 as shown in Figs. 1 and 3 and at the other end to the lower side of the plate 47 with which said form is connected. By this construction therefore I am enabled to control the movement of all the forms by 20 a suitable lever, and to cause them to press uniformly against the shaping-die. The movement or travel of the various members being simultaneous, the entire periphery of the insole is shortened at once and there is 25 no space left between adjacent forms so that an evenly formed lip is produced on the insole. The collar 30 on the slide rod 16 is so adjusted that when it contacts with the lower guide 17 the shaping-die will be substantially 30 in the position shown in Fig. 4, the bottom surface of the flange 20 on the shaping-die being below the external forms an amount dependent upon the thickness of material to be shaped.

35 At 74 and 75 are shown guides secured to the table A in proper relation with the work-support so that the blank to be shaped, this being of the form shown in Fig. 5, may be accurately placed on the work-support 40 by the operator. The guides 74 are each secured to a member 76 by the slot and pin connections 77 and the members 76 are in turn secured to the table by the slot and pin connection 78 all as clearly shown in Figs. 1 45 and 3. The guides 75 are also supported on the table A in the position shown in Figs. 1 and 3 and are secured thereto by the slot and pin connection 79. These members may be made in any convenient form but are conveniently 50 made of thin strips of metal of the form and shape shown in Fig. 2 having a depending front end 80 adapted to contact with the edge of the material of which the blank consists. They extend inwardly 55 toward the work-support and may be adjusted through the slot and pin connections described to have the proper relative position with the work-support for blanks of any size to be operated upon.

60 The blank is cut substantially in the shape shown in Fig. 5, the toe portion being somewhat larger than the toe portion of the lower surface 20 of the shaping-die plate 19. The guides 74 and 75 are so adjusted that 65 when the toe portion 791 of the blank con-

tacts with the guides 75 and the edges 81 contact with the guides 74, the edge of the toe portion will protrude beyond the bottom surface of the shaping-die plate 19, and the edge of the work-support 32. The 70 shaping-die 19 is then moved downwardly into contact with the blank holding it firmly in position on the work-support. The external forms 39, 40 and 48 are in the position shown in Fig. 1 and should be adjusted 75 so that there is a small space between them and the shaping-die as shown in Fig. 9. The shaping-die and work-support are then moved downwardly against the spring 37 until the collar 30 has come into contact 80 with the lower guide 17 of the frame C which causes the work-support and shaping-die to stop in the position shown in Fig. 4. During this downward movement the shaping-die and work-support pass through 85 the external forms and the protruding edge of the blank comes into contact with their inner edges and is turned up by them in the manner shown in Figs. 9 and 10. The lever 55 is then thrown into the position 90 shown in Fig. 3 and the external forms 39, 40 and 48 are simultaneously moved inwardly toward the shaping-die plate 19. It will be seen from Fig. 4 that this will cause 95 a portion of the upwardly extending edge of the blank to be folded sharply over and about the flange 20 as shown at 82 the remainder of said edge 83 being compressed in an upright position between the edge of the external forms and that of the shaping-die 100 plate 19. The collar 30 being located so that the flange 20 is below the external forms a distance slightly less than the thickness of the material to be formed, it will be seen 105 that the inward movement of the external forms over the flange will iron the material out over the upper edge of the flange 20 and draw it tightly into the position shown in Fig. 4 of the drawings. The heavy pressure brought to bear on the material by the lever 110 55 compresses the material and shapes it as shown, so that when removed from the machine it will retain the form shown in Fig. 6. This construction is important for I have found that if uniform pressure is brought to 115 bear simultaneously about all sides of the toe portion of the blank and properly tempered leather is employed that portion of the leather which is required to stretch slightly and that portion which is required to be 120 crowded together will readily do so, whereas if pressure is not applied to all parts simultaneously it is practically impossible to form the lip. The toe form 48 is so constructed that the portion 52 of said form is 125 not quite concentric with the corresponding portion of the shaping-die plate but a somewhat greater space is left between the two members about the toes. The sharp turn made in the lip 83 at this point produces a 130

slight fullness in the leather to accommodate which and to prevent injury to the stock at this point the extra space is left. It is found that if the proper pressure is applied the article will retain its form without the application of heat, but to expedite work the dies will ordinarily be heated. After pressure for sufficient time has been brought to bear on the blank, the lever is thrown back into the position shown in Fig. 1, the shaping-die is raised by the lever 23 and the shaped blank is then removed and replaced by another.

It will be seen from Fig. 6 that the blank thus formed has a lip 82 and a lip or channel flap 83 which corresponds with the channel flap formed in a well known channeling machine. The lip or channel flap thus formed, however, is of the full thickness of the material and, therefore, has all the strength possible to be obtained from the material used. It is furthermore in an upright or substantially vertical position and, therefore, is readily adapted to be sewed to the upper and welt of the shoe.

The insole member just described may be conveniently termed the outer insole member for it is designed to be used in connection with an inner insole member shown in Fig. 8 which is cut and shaped to fit snugly within the outer member so that the lip of one lies contiguous with that of the other.

In Fig. 7 is shown my machine provided with a shaping-die 85 adapted to be used in forming the inner member. The machine parts are exactly the same as described above with the exception of the shaping-die and work-support, the form of shaping-die and work-support shown at 85 and 86 in Fig. 7 being employed. The shaping-die consists of a flat plate similar to the one described above with the exception it has no flange or bottom plate as is necessary when the outer insole member is to be formed and is slightly smaller than the plate 19 of the old shaping-die. The external pressure members 39, 40 and 48 may be properly adjusted for the smaller die and work-support at the bolt and slot connections 46. The collar 30 should be so adjusted on the rod 16 that it strikes the lower guide 17 when the die and work-support are moved downwardly into the position shown in Fig. 7. The blank employed is substantially the same as the blank described heretofore with the exception that it is slightly smaller. It is provided preferably with two incisions 87 in order to permit the outer edge of the toe portion to be formed into the lip 88 shown. After properly adjusting the guides 74 and 75 the blank is clamped on the work-support in the same manner as the outer member and the machine operated as before de-

scribed. The inner insole member is thus adapted to fit within the outer insole member. The lips 88 and 83 together forming a thick strong channel flap.

Fig. 11 illustrates the use of the machine for the purpose of assembling the insole members. The inner insole member shaping-die and outer insole member work-support are employed and the combined members compress between the external forms. Any well known form of cement may be employed so that the members are thus given a final shaping pressure and firmly secured together.

What I claim is:

1. The improved insole forming machine comprising a shaping die, side forms and an end form movably mounted about said die and having operating surfaces coöperating therewith, separate toggle joint connections for said end form and each of said side forms, and a bell crank lever forming one of said toggles to which each of said other toggles is connected and by which all of said toggles may be simultaneously operated to cause said forms to be simultaneously moved against the shaping die to compress and form the material.

2. In a machine of the character described the improved presser mechanism for forming insoles comprising a shaping-die having a pressure surface the shape of the insole to be formed, a flange of uniform width protruding outwardly about said pressure surface, external presser members movably mounted about said shaping-die and having pressure surfaces coöperating with the pressure surface of said shaping-die and means for moving said external presser members against the pressure surface of said shaping-die and adjacent said flange whereby a blank placed on said shaping-die is folded sharply upon itself over said flange and a lip formed between the pressure surfaces of said external forms and the pressure surface of said shaping-die.

3. In a machine of the character described, the combination of a shaping die having a substantially arc shaped convex toe portion, and a toe form having a substantially arc shaped concave portion adapted to coöperate therewith, the arc shaped portion of said toe form being of less diameter than the coöperating convex surface of said shaping die so that a space is left between the members when in contact.

In testimony whereof I affix my signature, in presence of two witnesses.

EUGENE H. TAYLOR.
